UNITED STATES PATENT OFFICE.

BERTINIUS LARSEN AND WALTER H. PARKIN, OF NILES, MICHIGAN, ASSIGNORS TO NATIONAL-STANDARD COMPANY, OF NILES, MICHIGAN.

ROTARY BLOWER.

1,111,160.

Specification of Letters Patent. Patented Sept. 22, 1914.

Application filed November 15, 1913. Serial No. 801,289.

To all whom it may concern:

Be it known that we, BERTINIUS LARSEN and WALTER H. PARKIN, citizens of the United States, residing at Niles, Michigan, have invented certain new and useful Improvements in Rotary Blowers, of which the following is a specification.

This invention relates to improvements in rotary blowers.

10 The main objects of this invention are: First, to provide in a rotary blower an improved piston or drum structure. Second, to provide in a rotary blower, an improved piston blade or movable abutment. Third, to provide in a rotary blower, improved piston blade or movable abutment shoes and connections therefor to the piston blades. Fourth, to provide an improved rotary blower which may be adjusted to take up 20 wear and to adapt the blower for high and low pressures. Fifth, to provide in a rotary blower an improved bearing and journal packing. Sixth, to provide an improved rotary blower in which the parts are simple 25 and economical to produce and easily assembled, and one which is very durable in use.

Further objects, and objects relating to structural details, will definitely appear 30 from the detailed description to follow.

We accomplish the objects of our invention by the devices and means described in the following specification.

The invention is clearly defined and pointed out in the claims.

A structure which is a preferred embodiment of our invention is clearly illustrated in the accompanying drawing forming a part of this specification, in which:

40 Figure I is a perspective view of a structure embodying the features of our invention. Fig. II is an end elevation looking from the right of Fig. I. Fig. III is a vertical transverse section on a line corresponding to line 3—3 of Fig. IV, the piston blades or movable abutments and certain parts attached thereto being in full lines. Fig. IV is an elevation view mainly in longitudinal vertical section, on a line corresponding to line 4—4 of Fig. III. Fig. V is a transverse section on a line corresponding to line 5—5

of Fig. IV. Fig. VI is an enlarged detail section on a line corresponding to line 6—6 of Figs. IV and V, showing structural details of the piston and piston blades or movable abutments. Fig. VII is a detail transverse section on a line corresponding to line 7—7 of Fig. IV, showing details of the piston blade or movable abutment bearings in piston or drum. Fig. VIII is a detail transverse section on a line corresponding to line 8—8 of Fig. IV, showing further details of the piston blade bearing in the piston. Fig. IX is a side elevation of one form of the piston blade or movable abutment. Fig. X is a side elevation of the other form of piston blade or movable abutment. Fig. XI is an enlarged detail vertical section on a line corresponding to line 11—11 of Fig. IV, showing details of the adjusting means. Fig. XII is a perspective view of the piston body or drum. Fig. XIII is a detail perspective view of one of the piston head or drum head members by which the journals are connected thereto. Fig. XIV is an inside perspective view of the other piston head or drum head member. Fig. XV is a perspective view of the piston body or drum showing it as it is cast. Fig. XVI is a central longitudinal section through the piston or drum with the piston blades or movable abutments removed.

In the drawing, similar reference characters refer to similar parts throughout the several views, and the sectional views are taken looking in the direction of the little arrows at the ends of the section lines.

Referring to the drawing, the cylinder or cylindrical casing 1 is provided with an inlet 2 at one side, and a discharge 3 near the top at the opposite side. The cylinder is provided with removable heads 4 attached by the bolts 5 engaging the outwardly projecting flanges 6 at the ends of the cylinder. In practice, suitable packing rings, not shown in the accompanying drawing, are provided for these heads. The cylinder is mounted upon a suitable base or pedestal 7. The piston body or drum 8 is cast iron casting, preferably cored or chambered, as shown, with internal longitudinal radially disposed web portions 9 therein. The radial

slots 10 adapted to receive the movable abutments or piston blades 11 are disposed so as to extend through these web portions. The slots 10 are formed with dove-tailed recesses 12 in their side walls at each end and longitudinal grooves 13 adapted to receive and retain the Babbitt bearing facings 14 which face the slots and constitute the bearing surfaces for the piston blades 11.

10 The piston body or drum is cast in a single piece with a hub-like projection 15 at one end and is cast upon a cross 16 at the other end. This facilitates the casting of the piston drum or body and also the lathe work upon the same.

15 The piston end members or head members 17 are secured to the ends of the pistons by the bolts 31. These members 17 are of the same shape for convenience in manufacturing. They are preferably formed of steel, the piston journals 30 being integral therewith.

20 The members 17 are provided with central hub-like projections 29, that of the left hand member being recessed to receive the hub-like projection 15 on the piston body or drum. The end members 17 are provided with radial slot-like recesses 17¹ registering with the slots of the piston body or drum, 25 the recesses 17¹ being adapted to receive the journal blocks 18 for the piston blade shoes 19. The cylinder heads 4 are provided with annular groove-like bearings 20 for these shoes 19, the blocks 18 having bearing 30 pins 21 engaging the shoes. The blocks are provided with bearing shoulders for the shoes at the bases of the journals. The ends of the blades are notched at 22, while the blocks 18 are slotted at 23 to receive the ends 35 of the blades, and are rigidly secured thereto by the rivets 24. As the piston is revolved, the shoes traveling around in the bearing grooves 20, keep the blades in proper position, just out of contact with the 40 walls of the cylinder. The shoes 19 are inclined at 25 on their inner faces so that they readily pass the piston as the blades are moved in and out of the piston by the rotation thereof, which is eccentrically disposed 45 within the cylinder. The shoes are longitudinally curved to correspond to the curvature of the bearing groove 20. See Figs. V and VI. The shoes when thus formed and mounted on the blades are practically noiseless.

50 The blades are arranged in oppositely disposed pairs, one pair having central extensions 26 on their inner edges and the other pair, extensions 27 at each end spaced so as to receive the extensions 26 between 55 them. These extensions on the blades assist in supporting them when they are fully extended and at the same time, the blades do not interfere with one another as they are retracted, as the extensions interlap

when the blades are in their retracted positions within the piston. The blocks 18 not only serve as an effective attaching means for the shoes to the blades 11, but serve also as reinforcing and guiding members for the blades.

65 The cylinder heads 4 are provided with internal recesses 28 for the projections 29 of the members 17. The bearing members 32 are provided with attaching flanges 33 at their inner ends, which are secured to the cylinder heads by means of the screw bolts 34. The openings 35 in the cylinder heads are somewhat larger than the diameter of the journals 30 so as to permit the lateral adjustment of the journals therein. This 70 lateral adjustment is effected by making the holes 36 for the bolts 34 large enough to permit the adjustment of the bearing members, see Fig. IX, the holes being slot-like in form. The flanges 33 are supported by the wedges 37 which rest on the inclined wedge seats 38 provided therefor on the cylinder heads as shown. The supporting wedges 37 are inclined on their under sides, but are straight on their upper sides. They 75 are adjusted by means of the screws 39 arranged through downwardly projecting ears 40 in the wedges and threaded into the seats 38. The bearing members are clamped upon the wedges by means of the screws 41 arranged through the projecting ears 42 at the top of the cylinder heads and threaded into the flanges 33. See Figs. I and IV. By thus arranging the parts, the bearings 80 may be adjusted to take up wear, and also, and this is also a very important function, to adjust the piston or drum relative to the cylinder. When operating the blower on high pressures, it is necessary that the clearance between the drum and cylinder wall 85 shall be very slight. This, however, is not necessary when only low pressures are desired, and it is found that a great saving 90 power is obtained by reducing the air compression at this point, which may, as will 95 be readily understood, be accomplished 100 through the adjustment described. The bearing members 32 are provided with lubricant chambers 43.

105 The structure illustrated is of the ring lubricator type, the bushings 44 being provided with grooves 45 for the oil rings 46, which depend into the lubricant chamber in the well-known way. The bearing bushings are provided with oil discharge openings 53 and 54 in their bottoms, the openings being located at the outer sides of the oil rings. The bushings also have cavities 110 115 120 125 125 communicating with the discharge openings 54 which cavities serve to collect the lubricant at the outer ends of the journals and through the openings 54 redeliver it to the reservoir. The oil rings are introduced

into the bearing members through the transverse slot-like openings 56 in the tops of the bearing members. The oil rings are adjustable laterally with the bushings. The bearing bushings 44 are adapted also as packing glands, being provided with ear-like projections 47 at their outer ends through which the adjusting screws 48 are arranged, the screws being tapped into the ends of the bearing members 32. The packing rings 49 are arranged in suitable seats 50 provided therefor, in the bearing member. By adjusting the glands upon the packing members, they are compressed to form a tight joint at this point. The bearing bushings are readily removable so that they can be renewed as desired. One journal of the piston is provided with a driving wheel 51, the outer end of the journal being supported by the pedestal 52.

By forming the drum or piston body as we have illustrated and described, we secure a structure in which the body can be readily formed of cast iron which is a satisfactory material for this purpose, and also, may be formed in one piece. The heads or drum ends, when attached, not only serve to secure the journals to the piston body or drum, but also serve as reinforcing and supporting members. By providing the Babbitt bearing surfaces, perfect bearings for the blades can be secured of a material highly satisfactory for bearing surfaces without expensive machine work, and should the bearings become worn, they can be readily knocked out and new bearings provided. By adjusting the bearing members vertically, the drum is brought into contact with the cylinder wall as desired.

40 In operating on high pressures, it is quite necessary that close contact be had between the walls of the cylinder and the drum, but in operating on low pressures, less closeness is required, thus not only reducing wear on the blower, but also, requiring very much less power to operate. The contact may be regulated by adjustment of the journals. The adjustment may be used to compensate for wear on the journals and their bearings. 45 The journal bushings serve, as stated, the purpose of packing glands for the journals, and at the same time, they can be readily renewed as occasion requires.

Our improved blower is very efficient, requires little power to operate, and is simple and economical to produce.

We have not attempted to illustrate various modifications we contemplate as we believe the disclosure made will enable those skilled in the art to which this invention relates to adapt or embody the same as may be deemed desirable. We desire, however, to be understood as claiming our improvements specifically in the form illustrated as

well as broadly within the scope of the appended claims.

Having thus described our invention what we claim as new and desire to secure by Letters Patent is:

1. In a structure of the class described, the combination of a cylinder, heads therefor having annular groove-like shoe ways in their inner sides; a cast iron piston body having piston blade slots therein extending from end to end of the body, said body being cast integrally with a hub-like projection at one end, the end of said hub-like projection being unslotted; steel end members secured to the ends of said body and having journals integral therewith and radial slots registering with the blade slots of said body and hub-like projections, the projection of one end member being recessed to receive said hub-like projection on said body, said cylinder heads being recessed to receive said hub-like projection on said end members; piston blades disposed in said slots in said piston body; shoe journal blocks slotted to receive said piston blades and rigidly secured thereto, said blocks being disposed in said slots in said end members and provided with journals projecting into said shoe ways; and shoes arranged on said journals to travel in said ways as the piston revolves.

2. In a structure of the class described, the combination of a cylinder, heads therefor having annular groove-like shoe ways in their inner sides; a cast iron piston body having piston blade slots therein extending from end to end of the body, said body being cast integrally with a hub-like projection at one end, the end of said hub-like projection being unslotted; steel end members secured to the ends of said body and having journals integral therewith and radial slots registering with the blade slots of said body, one end member being recessed to receive said hub-like projection on said body; piston blades disposed in said slots in said piston body; shoe journal blocks slotted to receive said piston blades and rigidly secured thereto, said blocks being disposed in said slots in said end members and provided with journals projecting into said shoe ways; and shoes arranged on said journals to travel in said ways as the piston revolves.

3. In a structure of the class described, the combination of a cylinder, heads therefor having annular groove-like shoe ways in their inner sides; a cast iron piston body having piston blade slots therein extending from end to end of the body, said body being cast integrally with a hub-like projection at one end, the end of said hub-like projection being unslotted; steel end members secured to the ends of said body and having journals integral therewith and radial slots

registering with the blade slots of said body and hub-like projections, the projection of one end member being recessed to receive said hub-like projection on said body, said 5 cylinder heads being recessed to receive said hub-like projection on said end members; piston blades disposed in said slots in said piston body; and shoes connected to said blades to travel in said ways as the piston 10 revolves.

4. In a structure of the class described, the combination of a cylinder, heads therefor having annular groove-like shoe ways in their inner sides; a cast iron piston body 15 having piston blade slots therein extending from end to end of the body, said body being cast integrally with a hub-like projection at one end, the end of said hub-like projection being unslotted; steel end members secured to the ends of said body and having journals integral therewith, one end member being recessed to receive said hub-like projection on said body; piston blades disposed in said slots in said piston body; 20 and shoes connected to said blades to travel in said ways as the piston revolves.

5. In a structure of the class described, the combination of a cylinder, heads therefor having annular groove-like shoe ways 30 in their inner sides; a piston body having piston blade slots therein extending from end to end; end members secured to the ends of said body and having journals thereon and radial slots registering with the blade 35 slots of said body; piston blades disposed in said slots in said piston body; shoe journal blocks slotted to receive said piston blades and rigidly secured thereto, said blocks being disposed in said slots in said end members and provided with journals projecting 40 into said shoe ways; and shoes arranged on said journals to travel in said ways as the piston revolves.

6. In a structure of the class described, the 45 combination of a cylinder, heads therefor having annular groove-like shoe ways in their inner sides; a piston body having piston blade slots therein extending from end to end; end members secured to the ends of 50 said body and having journals thereon and radial slots registering with the blade slots of said body; piston blades disposed in said slots in said piston body; shoe journal blocks secured to said piston blades and disposed 55 in said slot in said end members and provided with journals projecting into said shoe ways; and shoes arranged on said journals to travel in said ways as the piston revolves.

7. A rotary blower comprising a cast iron 60 piston body having internal longitudinal radially disposed webs with radial piston blade slots therein extending from end to end of the body, said body being cast integrally with a hub-like projection at one end,

the end of said hub-like projection being 65 unslotted; steel end members secured to said body and having piston journals integral therewith and radial slots registering with the blade slots of said body, one end member being recessed to receive said hub-like projection on said body; piston blades disposed in said slots in said piston body; and shoe journal blocks secured to said blades and disposed in said slots in said 70 end members.

8. A rotary blower comprising a cast iron piston body having radial piston blade slots therein extending from end to end, said body being cast integrally with a hub-like projection at one end, the end of said hub-like projection being unslotted; steel end members secured to said body and having piston journals integral therewith and radial slots registering with the blade slots of said body, one end member being recessed to receive said hub-like projection on said body; piston blades disposed in said slots in said piston body; and shoe journal blocks secured to said blades and disposed in said slots in 80 said end members.

9. A rotary blower comprising a cast iron piston body having internal longitudinal radially disposed webs with radial piston blade slots therein extending from end to end of the body, said body being cast integrally with a hub-like projection at one end, the end of said hub-like projection being unslotted; and steel end members secured to said body and having piston journals integral therewith, one end member being recessed to receive said hub-like projection on 95 said body.

10. A rotary blower comprising a cast iron piston body having radial piston blade slots therein extending from end to end, said body being cast integrally with a hub-like projection at one end, the end of said hub-like projection being unslotted; and steel end members secured to said body and having piston journals integral therewith, one end member being recessed to receive said hub-like projection on 100 said body.

11. In a structure of the class described, the combination of a cylinder; heads therefor having annular groove-like shoe ways in their inner sides; a piston provided with radial piston blade slots; piston blades disposed in said slots; shoe journal blocks slotted to receive said piston blades and rigidly secured thereto, said blocks being provided 115 with journals projecting into the shoe ways and with shoulders at the bases of the journals; and shoes arranged on said journals to travel in said ways as the piston revolves, said shoes being in bearing engagement with 120 said shoulders on said blocks, their inner faces being inclined outwardly therefrom.

12. In a structure of the class described,

the combination of a cylinder, heads therefor having annular groove-like shoe ways in their inner sides; a piston provided with radial piston blade slots; piston blades disposed in said slots; shoe journals secured to said blades to project into said ways; and shoes arranged on said journals to travel in said ways as the piston revolves, the inner faces of said shoes being inclined outwardly.

18. In a structure of the class described, the combination with the cylinder, heads therefor; a piston provided with radially movable piston blades disposed eccentrically within the cylinder; journals therefor projecting through the cylinder heads; journal bearing members bolted to said heads, the bolt openings being enlarged to permit vertical adjustment of said bearing members; inclined wedge seats on said cylinder heads below said journals; adjusting wedges arranged on said seats and engaging said bearing members, said wedges being inclined on their under sides to coact with said inclined wedge seats; screws for adjusting said wedges on their said seats; and screws carried by the cylinder heads engaging said bearing members opposite said adjusting wedges.

30 14. In a structure of the class described, the combination with the cylinder, heads therefor; a piston provided with radially movable piston blades disposed eccentrically within the cylinder; journals therefor projecting through the cylinder heads; journal bearing members bolted to said heads, the bolt openings being enlarged to permit vertical adjustment of said bearing members; wedge seats on said cylinder heads; adjusting wedges arranged on said seats and engaging said bearing members, said wedges being inclined to coact with said inclined wedge seats; and screws for adjusting said wedges on their said seats.

45 15. In a structure of the class described, the combination with the cylinder, heads therefor; a piston provided with radially movable piston blades disposed eccentrically within the cylinder; journals therefor projecting through the cylinder heads; journal bearing members bolted to said heads, the bolt openings being enlarged to permit vertical adjustment of said journal members; wedge seats on said cylinder heads; and adjusting wedges arranged on said seats and engaging said bearing members.

60 16. In a structure of the class described, the combination of a cylinder, heads therefor, a piston provided with radially movable piston blades disposed eccentrically within the cylinder, journals therefor projecting through the cylinder heads, the cylinder heads having openings for said journals

of such size to permit the lateral adjustment of the journals therein, and journal bearing members mounted on the outer sides of said heads for lateral adjustment whereby the piston may be adjusted within the cylinder.

17. In a structure of the class described, the combination with the cylinder provided with a suitable head, a rotary piston, a journal therefor projecting through said head, a journal bearing member on said head adapted to receive a bearing bushing and having an oil reservoir therein and transverse openings at the top adapted to receive oil rings, a bushing arranged in said bearing member for longitudinal adjustment therein, said bushing being slotted to receive oil rings and having oil discharge openings in its bottom located at the outer sides of the oil rings, there being an internal cavity near the outer end of said bushing communicating with one of said oil discharge openings thereof, oil rings arranged in said slots in said bushing, a packing ring arranged at the inner end of said bushing, said bearing member being provided with a packing ring seat at the inner end of said bushing, and means for adjusting said bushing longitudinally whereby it constitutes a packing gland, said oil rings being adjustable laterally with said bushing.

18. In a structure of the class described, the combination with the cylinder provided with a suitable head, a rotary piston, a journal therefor projecting through said head, a journal bearing member on said head adapted to receive a bearing bushing and having an oil reservoir therein and transverse openings at the top adapted to receive oil rings, a bushing arranged in said bearing member for longitudinal adjustment therein, said bushing being slotted to receive oil rings and having an oil discharge opening in its bottom and an internal oil collecting cavity near its outer end communicating with said opening, oil rings arranged in said slots in said bushing, a packing ring arranged at the inner end of said bushing, and means for adjusting said bushing longitudinally whereby it constitutes a packing gland, said oil rings being adjustable laterally with said bushing.

19. In a structure of the class described, the combination with the cylinder provided with a suitable head, a rotary piston, a journal therefor projecting through said head, a journal bearing member on said head adapted to receive a bearing bushing and having an oil reservoir therein and transverse openings at the top adapted to receive oil rings, a bushing arranged in said bearing member for longitudinal adjustment therein, said bushing being slotted to receive oil rings, oil rings arranged in

said slots in said bushing, a packing ring arranged at the inner end of said bushing, and means for adjusting said bushing longitudinally whereby it constitutes a packing gland, said oil rings being adjustable laterally with said bushing.

In witness whereof, we have hereunto set

our hands and seals in the presence of two
witnesses.
